[57] CLAIM

The ornamental design for a lightning deterrent, as shown and described.

DESCRIPTION

FIG. 1 is a front elevational view of a lightning deterrent showing my new design;

FIG. 2 is a top plan view thereof;

FIG. 3 is a bottom plan view thereof; and,

FIG. 4 is a side elevational view thereof, with the opposite sides being a mirror image.

*Fig. 1**Fig. 2**Fig. 3**Fig. 4*
